No. 37,293.

Patented January 10, 1905.

UNITED STATES PATENT OFFICE.

CHRISTIAN SEIDEL, OF NEW YORK, N. Y.

DESIGN FOR TRIMMING.

SPECIFICATION forming part of Design No. 37,293, dated January 10, 1905.

Application filed December 17, 1904. Serial No. 237,298. Term of patent 3½ years.

To all whom it may concern:

Be it known that I, CHRISTIAN SEIDEL, a citizen of the United States, and a resident of the city of New York, borough of the Bronx, in 5 the county and State of New York, have invented a new, original, and ornamental Design for Trimming, reference being had to the accompanying drawing, in which the figure shows in plan my new design for a trimming.

I claim as new and desire to secure by Letters Patent—

The ornamental design for a trimming, herein shown.

CHRISTIAN SEIDEL.
